WALL RACK FOR NAILS OR THE LIKE

Joseph J. Langworthy, 1818 Bissell Ave.,
Richmond, Calif. 94801

Filed Feb. 2, 1971, Ser. No. 112,102

Term of patent 14 years

Int. Cl. D6—99

U.S. Cl. D6—130

FIG. 1

FIG. 2

FIG. 3

FIG. 4

FIG. 1 is a top plan view of a wall rack for nails or the like showing my new design.

FIG. 2 is a front elevational view thereof;

FIG. 3 is a side elevational view thereof; and

FIG. 4 is a rear elevational view thereof.

I claim:

The ornamental design for a wall rack for nails or the like, substantially as shown.
